UNITED STATES PATENT OFFICE.

HARRY ALPHONSE WIDMER, OF LONDON, ENGLAND.

FOUNTAIN-PEN AND THE LIKE.

1,296,890.

Specification of Letters Patent. Patented Mar. 11, 1919.

Application filed December 6, 1918. Serial No. 265,632.

To all whom it may concern:

Be it known that I, HARRY ALPHONSE WIDMER, a subject of the King of Great Britain and Ireland, residing at 32 to 34 5 Clerkenwell road, London, E. C., England, have invented new and useful Improvements in and Relating to Fountain-Pens and the like, of which the following is a specification.

10 The present invention relates to improvements in the fountain pen or other writing instrument in which a blotting attachment is combined with the pen or the like in such a manner that it can be slid into the interior 15 of the cap of the pen when out of use and easily ejected from said cap when required. In the preferred arrangement the blotting attachment formed an independent unit and therefore had the disadvantage in practice 20 that it was sometimes mislaid and not at hand when required.

According to the present invention a fountain pen is provided with a blotting attachment of the type described in which 25 the cap is provided with an opening adapted to be closed by a rotating shutter through which opening the blotter is adapted to project; the movement of the shutter on or off the opening being such that it is adapted 30 to force said blotter into the cap against the influence of its spring or to release said attachment and allow it to take up a position projecting through said opening.

My invention is illustrated by way of 35 example in the accompanying drawings, in which—

Figure 1 shows a sectional view of the pen with the shutter in position over the opening in the cap.

40 Fig. 2 shows a sectional view with the shutter in the off position and the blotter projecting through the opening.

Fig. 3 shows a detail view of the opening in the cap.

45 Fig. 4 shows a detail view of the blotter, and

Fig. 5 shows a detail view of the shutter.

Referring now to the drawings:

1 indicates the pen, 2 indicates the cap 50 provided with deep bearings 3 adapted to receive the ends of the spindle 4 on which is mounted the blotter 5. 6 indicates the spring tending to project the blotter through the opening 7 as shown in Fig. 2. The

cap is provided with a rotatable shutter 8 55 shown in detail in Fig. 5. This shutter is adapted to be turned so as to cover the opening and to compress the blotter into the cap against the influence of its spring 6 or turned to a position in which it is off 60 the opening and consequently releases the blotter and allows it to project through said opening 7 as shown in Fig. 2.

The blotting attachment of my invention is arranged so that it can be easily dis- 65 mantled and renewed when desired. The cap is provided with a screw-on end piece 10 shown in Figs. 1 and 2. When this end piece is removed the shutter can be withdrawn over the end of the cap, thereby 70 opening the bearings 3 and allowing the blotter to be lifted with its spindle out of said bearings.

What I claim is:—

1. A blotting attachment for fountain 75 pens and other instruments with ink reservoirs comprising a pen, a cap for said pen, a blotting attachment mounted within said cap and adapted to register with an opening in said cap, a spring adapted to pro- 80 ject said blotting attachment through said opening and a rotatable shutter adapted to be moved off said opening to allow the attachment to project therethrough or to be moved over said opening to compress said 85 attachment into the cap against the influence of its spring.

2. A blotting attachment for fountain 90 pens and other instruments with ink reservoirs comprising a pen, a cap for said pen, 90 bearings in said cap, a spindle mounted in said bearings, a blotting attachment carried by said spindle and adapted to register with an opening in said cap, a spring adapted to project said blotting attachment 95 through said opening and a rotatable shutter adapted to be moved off said opening to allow the attachment to project therethrough or to be moved over said opening to compress said attachment into the cap 100 against the influence of its spring.

3. A blotting attachment for fountain pens and other instruments with ink reservoirs comprising a pen, a cap for said pen, bearings in said cap, a spindle mounted in 105 said bearings, a blotting attachment carried by said spindle and adapted to register with an opening in said cap, a spring adapted to

project said blotting attachment through said opening, a rotatable shutter adapted to be moved off said opening to allow the attachment to project therethrough or to be moved over said opening to compress said attachment into the cap against the influence of its spring, end pieces on said

shutter adapted to retain the spindle of the blotting attachment in position in its bearings and a screw-on end piece adapted to 10 retain said shutter in position on the cap.

In testimony whereof I sign my name to this specification.

HARRY ALPHONSE WIDMER.
